UNITED STATES PATENT OFFICE.

JAMES HARRY NICHOLSON, OF NEW YORK, N. Y., ASSIGNOR TO FREEMAN, DOBBIN FIREPROOFING COMPANY, OF NEW YORK, N. Y., A CORPORATION OF NEW YORK.

WALL-FURRING.

SPECIFICATION forming part of Letters Patent No. 757,489, dated April 19, 1904.

Application filed August 27, 1903. Serial No. 171,024. (No model.)

To all whom it may concern:

Be it known that I, JAMES HARRY NICHOLSON, of New York, in the county of New York and State of New York, have invented certain new and useful Improvements in Wall-Furring; and I do hereby declare the following to be a full, clear, and exact description of the invention, such as will enable others skilled in the art to which it appertains to make and use the same.

The primary object of this invention is to provide improved studding for fireproof building construction.

A further object is to provide improved means complementary to the studding for holding the fireproof slabs in position.

The invention will be hereinafter fully set forth, and particularly pointed out in the claims.

In the accompanying drawings, Figure 1 is a perspective view. Fig. 2 is a sectional view of the studding. Figs. 3 and 4 are edge and plan views, respectively, of the preferred form of clip. Fig. 5 is a slight modification thereof. Fig. 6 shows the end stud. Fig. 7 shows slabs in position.

Referring to the drawings, 1 designates a building-wall of brick or other construction.

2 designates the studding employed at either end of a section of furring. It is shown as consisting of strips, preferably of wood, square or rectangular in cross-section and provided with metallic sheathing. These strips are designed to be secured to the building-wall in a vertical position to support the slabs 3 at their side edges, thus providing the necessary air-space between the wall and furring.

4 designates the studding designed to accommodate adjacent slabs. This consists of a metallic member or a series thereof corresponding in height to that of the vertical series of slabs and provided with angular portions 5, having flanges 6, the latter designed to be secured to the building-wall. The studding is preferably made from a single piece of metal bent at its sides to form the angular portions and flanges. The bridge of the studding 4 is designed to form a seat for the slabs 3, its angular portions 5 corresponding in length

to the thickness of the strips 2 to maintain the 50 air-space between the slabs and building-wall. The studding is provided with a series of longitudinal slots 7, designed to register with the space intermediate adjacent slabs.

8 designates the clips or securing members 55 by which the slabs are secured to the studding 4. When in position, these clips are of approximately I shape and are designed to have their central body portions 9 movably held within slots 7, so that their inner lateral flanges 60 10 will engage the inner face of the studding, while the outer flanges 12 overlap the slabs and retain the latter in place. (See Fig. 7.) As shown in Figs. 3 and 4, the clips may be made from a metal plate cut to form a tongue 65 constituting the central body portion 9 and the latter divided longitudinally at its free end to form ears or flanges designed to be bent in opposite directions to constitute the inner securing members 10. In the modification 70 shown in Fig. 5 the plate is divided longitudinally at both of its ends, and the adjacent flanges thus formed are bent in opposite directions. In the use of either form the clip is positioned in the studding in the manufacture of the latter and the inner flanges bent to 75 their normal positions.

In constructing the furring the studs carrying the clips are first secured to the building-wall. The side edges of the end slabs of a section are secured to studs 2 and the other edges placed in contact with studs 4, after which the clips are moved through their slots and slipped over the slabs to hold the latter, the frictional engagement of the clips insuring their remaining in their adjusted positions, although the end walls of the slots would prevent the clips entirely slipping from the slabs.

The advantages of my invention are apparent to those skilled in the art to which it relates. It will be noted that the stud 4, being in one piece, insures the slabs being held in the same plane and relative positions. This advantage is obviously not attainable where separate studding members are employed to support adjacent slabs. It will further be noted that the clips and studding are readily assembled in the manufacture and that the for-

mer are easily slipped into position to support the slabs.

I claim as my invention—

1. In a wall construction, the combination with slabs arranged in parallel series, of studding designed to support the slabs of adjacent series, such studding consisting of an approximately U-shape member having its bridged portion forming seats for the slabs, and means for securing the slabs to the studding.
2. In a wall construction, the combination with slabs arranged in parallel series, of studding designed to support the slabs of adjacent series, such studding consisting of an approximately U-shape member having its bridged portion forming seats for the slabs and provided with a series of slots, clips movable in such slots and normally engaging the studding at their inner ends and their outer ends engaging and holding the slabs to the studding.
3. In a wall construction, a stud designed to accommodate the adjacent edges of fireproof slabs, such stud having parallel angular portions provided with flanges designed to be secured to a wall or other support, the main body portion of such stud spanning the edges of adjacent slabs and having a slot designed to register with the space intermediate such adjacent slabs, and a clip designed to be accommodated by such slot and having inner and outer lateral portions designed to engage, respectively, the inner face of the stud and the outer faces of the slabs.
4. In a wall construction, a stud designed to accommodate the adjacent edges of fireproof slabs, such stud consisting of a single piece of metal bent to form parallel angular portions and the latter bent to form flanges designed to be secured to a wall or other support, the main body portion of such stud spanning the edges of adjacent slabs, and having a slot designed to register with the space intermediate such adjacent slabs, and a clip designed to be

accommodated by such slot and having inner and outer lateral portions designed to engage, respectively, the inner face of the stud and the outer faces of the slabs.

5. In a wall construction, a stud having a bridging portion designed to span the edges of adjacent slabs to form seats therefor, such bridging portion having a slot designed to register with the space intermediate such slabs, and a clip designed to secure the slabs to the stud, such clip having outer lateral portions designed to engage the slabs, and a body portion designed to be accommodated between such slabs and within such slot and having its end divided, such divided portions being bent in opposite directions to engage the inner face of the stud.

6. In a wall construction, the combination with the slabs, and studs consisting of strips having metallic sheathing designed to support such slabs at one edge, of studs having bridging portions forming seats for the edges of adjacent slabs and provided with a vertical series of longitudinal slots designed to register with the space intermediate such slabs, and clips having outer flanges and central body portions, the former designed to engage the slabs and the latter to be accommodated by said slots and having their free ends divided, such divided portions being designed to be bent to form inner flanges to engage the inner faces of the studs.

7. As an article of manufacture, a U-shape stud for wall-furring having a slot in its bridged portion, and an I-shape clip having its body portion accommodated by said slot.

In testimony whereof I have signed this specification in the presence of two subscribing witnesses.

J. HARRY NICHOLSON.
